UNITED STATES PATENT OFFICE.

OSCAR L. WILSON, OF FORRESTON, ILLINOIS.

DESIGN FOR A POUNDER FOR WASHING-MACHINES.

SPECIFICATION forming part of Design No. 31,047, dated June 20, 1899.

Application filed May 19, 1899. Serial No. 717,504. Term of patent 3½ years.

To all whom it may concern:

Be it known that I, OSCAR L. WILSON, a citizen of the United States, residing at Forreston, in the county of Ogle and State of Illinois, have invented and produced a new and original Design for Pounders for Washing-Machines, of which the following is a specification.

The invention relates to a new and original design for pounders for washing-machines.

The essential feature of the design resides in a clothes-pounder having inclined sides and ends with tapering hoods curved in cross-section, the bottom of the pounder being located at a point between the upper and lower edges of the sides and having cylindrical cups.

The minor feature of the design resides in the bottom having slanted side and end portions.

In the drawings, Figure 1 is an inverted perspective view of a clothes-pounder for washing-machines, showing my new and original design. Fig. 2 is a similar view showing the top of the clothes-pounder.

Referring to the drawings, 1 designates a clothes-pounder oblong in plan view and pro-

vided with inclined sides 2 and ends 3 and having a horizontal top 4. The clothes-pounder is provided at its sides and ends with tapering hoods 5, curved transversely and having 30 their small ends arranged adjacent to the top 4 of the clothes-pounder.

The bottom 6 of the clothes-pounder is located at a point between the upper and lower edges of the sides and ends, and it is provided 35 with slanted side portions 7 and end portions 8. The slanted side portions form a longitudinal ridge 9, and the end portions 8 are triangular.

The clothes-pounder is provided with a row 40 of cylindrical cups 10, arranged along the ridge 9 of the bottom 6.

What is claimed is—

The design for a clothes-pounder herein shown and described.

In testimony that I claim the foregoing as my own I have hereto affixed my signature in the presence of two witnesses.

OSCAR L. WILSON.

Witnesses:

SAMUEL E. BROWN,
DANIEL W. FAGER.
